COMPOSITE MATRIX FOR PRINTING PLATES

Gunnar Rosenqvist, Oakmont, Pa.

Application January 2, 1932, Serial No. 584,473

4 Claims. (Cl. 154—46.5)

This invention relates to matrices utilized for making electro-type plates by galvano-plastic process, and it is among the objects thereof to provide a method of making composite matrices of laminated form which shall eliminate the tedious methods of making such matrices from wax only as heretofore practiced and which requires numerous heating and shaving operations that are eliminated by the present process.

10 A further object of the invention is the method of forming the imprint on the matrix in a manner to obtain perfect reproduction of the zinc or copper etching and the printing type on the matrix surface on which the electro-deposit is made to constitute the electro-type plate.

15 Still a further object of the invention is the method of making the composite matrix of layers of fibrous sheet material and a plastic material such as wax, the sheet material and wax being assembled in superposed relation with the wax sheets interposed between the layers of sheet material.

20 These and further objects of the invention will become more apparent from a consideration of the accompanying drawings constituting a part hereof in which like reference characters designate like parts and in which:

25 Figure 1 is a view in perspective illustrating the composite matrix in greatly exaggerated form; Figure 2 a cross-sectional view of a pair of pressure platens having the etching, the type, the matrix and other necessary elements disposed therebetween and illustrating one step in the process of making imprints in the composite matrices from which the electro-type are to be made;

30 Figure 3 a similar view of a somewhat different combination of elements particularly for presssing and locking the matrix and a supporting lead plate together;

35 Figure 4 is a side elevation of a portion of the lead plate, the matrix and the etching from which the impression is made;

40 Figure 5 a similar view without the etching;

45 Figure 6 an elevational view illustrating the method of making the matrix in a single operation for electro-type plates; and,

50 Figure 7 illustrates a section of the finished matrix.

55 With reference to Figure 1 of the drawings, the structure therein illustrated comprises a bottom layer of wax designated by the reference character 1, a relatively thick layer of fibrous sheet material of high porosity which is coated on its outer surfaces with wax, this layer being

designated by the reference character 2, and a plurality of alternate layers of wax or other plastic material 3 and relatively thin sheets of fibrous material 4, the latter being impregnated with the wax; and a final top layer 3 of wax, the wax layers and fibrous sheet material being relatively thin, and are shown of large size in the drawings for purpose of illustration only.

5 The assembled composite laminated body of Figure 1 is utilized in making matrices for electro-type plates in the following manner.

A retaining frame 5 is placed upon a pressure platen 6 and a supporting block 7 and printing types 8 are assembled in the frame 5, the block 7 supporting a zinc or copper etching 9 which 15 together with the type 8 constitutes the element from which the reproduction is to be made.

The composition laminated is graphited on the bottom side and is placed directly on the zinc or copper etching 9 and the type 8, the laminated 20 body being designated by the reference character 10 in the several figures of the drawings. A layer of untreated cloth or paper 11 is placed over the composite material and a resilient sheet material such as rubber 12 constitutes the final 25 layer of the assembled element upon which an upper platen 13 is placed. The layer 11 prevents tearing of the wax surface by the latter motion of rubber sheet 12 when subjected to pressure. The assembled structure is then disposed between a 30 pair of pressure platens of an hydraulic press to subject the composite matrix to pressure which causes the bottom layer 1 of wax to be pressed into the cavities of the etching and type as shown in the enlarged views of Figures 4 and 5 of the 35 drawings.

The material may be preheated before placing in the press or it may be pressed at room temperature. The pressure platens of the hydraulic press may if desired be heated by employing gas 40 burners or steam coils in the conventional manner to render the wax or other plastic material of the composite laminated structure more plastic during the pressing operation.

45 By utilizing the laminations of fibrous sheet material between successive layers of wax, the wax is prevented from being displaced laterally and the pressure is rendered more effective to force the wax into the cavities of the etchings and the printing type to obtain an efficient reproduction.

50 After the pressing operations, the platen 13 is removed and the rubber sheeting and the cloth 12 is stripped off, leaving the composite matrix 55 as the finished matrix for electro-type plates.

In another form of matrix the matrix as formed above is provided with a sheet lead support which becomes a permanent part of the matrix by a subsequent pressing operation as shown in Figure 3 of the drawings.

The composite wax and lead plate 10 and 15 respectively are shown on the etching 9 in Figure 4 of the drawings, after the pressing operation, and in Figure 5 the wax matrix 10 and lead support 15 are shown after removal from the etching. Both of the figures illustrate the lead supported matrix as produced by two pressing operations. It will be noted in Figures 4 and 5 that a space 17 remains between the material 10 which has been pressed into the etching, and the lead plate 15. However, the lead plate 15 is sufficiently displaced into the hollowness of the material 10 to interlock the joined layers and prevent distortion.

The bottom surface 18 of Figure 5 illustrates the matrix surface on which an electro-deposit is made to form the electro-type plates and surface 18 is rendered electrically conductive by coating it with graphite flakes or copper flakes in the conventional manner.

With reference to Figures 6 and 7 of the drawings, Figure 6 illustrates a method of forming the matrix with a sheet lead support in a single pressing operation as distinguished from the two step method employed in Figures 2 and 3 of the drawings, resulting in the product shown in Figures 4 and 5 of the drawings.

As shown in Figure 6, the supporting block and printing type 7 and 8 are assembled in the retaining frame 5 as heretofore described and suitably prepared wax material 10 is disposed on the surface of the etching 9 and the printing type.

Instead of employing an intermediate layer of untreated material, as the sheet 11 in Figure 2 of the drawings, the lead plate 15 is placed directly on the sheet material 10 and the sheet rubber material 12 is disposed on the plate 15. The top pressure platen 13 is then placed on the rubber sheet and the assembled structure is disposed between a pair of pressure platens of a press whereupon the application of pressure on the composite material 10 and its supporting lead sheet plate 15 is displaced in the manner shown in Figure 7 of the drawings to form the imprint on the bottom surface of the composite body.

It will be noted in contrast with the matrices shown in Figures 4 and 5, that the sheet lead in Figure 7 has substantially filled the space 17 of Figure 5, thereby producing a more effective inner lock of the matrix and the lead support.

The adhesive nature of the wax with which the supporting lead sheet intimately contacts also aids in holding these parts together as the upper surface of the wax is not graphitized or coated to prevent adherence as is the lower surface which constitutes the matrix surface on which the galvanoplastic material is deposited.

The edge of the finished matrices are insulated with wax as shown at 20, this insulation being produced by dipping the finished sheets in wax.

The matrix is then suspended in an electrolytic solution and the metal mold for the electro-type plate is deposited thereon by galvanoplastic process.

As shown in Figure 1 of the drawings, the layer 2 of fibrous material is substantially thicker than

the remaining sheets of material and is of a highly porous character to permit the escape of trapped air and this particular sheet is not impregnated with wax but is merely coated on its outer surfaces. Instead of utilizing the porous sheet 2, the top layer of the material may be coated with graphite which is partly removed to cause adherence of the lead sheet 15.

Where the matrix is joined with porous paper, the paper may be impregnated with a lacquer solution before coating it with wax. Such treatment will prevent the papers from swelling without interfering with its porous quality.

When the matrix surface is rendered conductive with or by dry methods, alcohol is sprayed with a spray gun on the surface before submerging it into the electrolytic solution.

It is evident from the foregoing description of this invention that composite wax and fibrous sheet material matrices made in accordance therewith provide simple and efficient means for making matrices for electro-type plates with a minimum amount of time and labor and in an inexpensive manner.

The composite matrix material can be made in large quantities by passing the sheet material from rolls through treating tanks to either impregnate or coat the sheet material as desired and then passing such treated material in proper assembled positions to suitable air treating towers.

The sheet wax material can be disposed between the layers of the treating material as it is passing out of the treating equipment and the assembled structures can be rendered compact by passing it through a pair of squeezing rolls.

I claim:

1. A composite matrix for making electro-type plates comprising alternate relatively thin layers of fibrous sheet material and plastic material assembled to constitute a unitary structure.

2. A composite matrix for making electro-type plates comprising a plurality of relatively thin layers of fibrous sheet material impregnated with plastic material and having layers of plastic material disposed therebetween, said layers being in superposed relation and joined to constitute a unitary structure.

3. A composite matrix for electro-type plates comprising a laminated structure of relatively thin fibrous sheet material, some of which have been impregnated with plastic material and others of which having their surfaces coated with plastic material, and layers of plastic material disposed between layers of said treating materials.

4. A composite matrix for electro-type plates comprising a laminated structure having a bottom layer of plastic material rendered electrically conductive, a second layer of relatively thick fibrous sheet material of a highly porous character having its outer surfaces coated with plastic material, and alternate layers of plastic material and relatively thin fibrous sheet material impregnated with plastic material assembled in superposed relation on said first named layers, and all of said layers being joined to constitute a unitary structure.

GUNNAR ROSENQVIST. 70
